DESIGN FOR A CLASP FOR A HANDBAG OR SIMILAR ARTICLE

John De Pasquale and Alexander Westerman,
Brooklyn, N. Y., assignors to Hardy Metal Specialties Inc., Brooklyn, N. Y., a corporation of New York

Application June 7, 1944, Serial No. 113,888

Term of patent 7 years

(Cl. D87—2)

To all whom it may concern:

Be it known that we, John De Pasquale and Alexander Westerman, both citizens of the United States, both residing at Brooklyn, in the county of Kings, city and State of New York, have invented a new, original, and ornamental Design for a Clasp for a Handbag or Similar Article, of which the following is a specification, reference being had to the accompanying drawing, forming part thereof.

In the drawing

Fig. 1 is a front elevational view of a clasp for a handbag or similar article showing my new design;

Fig. 2 is a side view thereof; and

Fig. 3 is a sectional view on the line 3—3 of Fig. 1.

We claim:

The ornamental design for a clasp for a handbag or similar article, substantially as shown.

JOHN DE PASQUALE.
